UNITED STATES PATENT OFFICE.

JAMES S. ARCUS, OF CHICAGO, ILLINOIS.

ROLL-TICKET-DISPENSING DEVICE.

1,332,194.

Specification of Letters Patent.

Patented Mar. 2, 1920.

Application filed July 3, 1916. Serial No. 107,285.

To all whom it may concern:
Be it known that I, JAMES S. ARCUS, a citizen of the United States, and a resident of Chicago, in the county of Cook and State of Illinois, have invented certain new and useful Improvements in Roll-Ticket-Dispensing Devices; and I do hereby declare that the following is a full, clear, and exact description thereof, reference being had to the accompanying drawings, and to the characters of reference marked thereon, which form a part of this specification.

This invention relates to a novel roll ticket dispensing device, such as is used in moving - picture shows, concessions for amusement parks and the like, and the invention consists in the combination and arrangement of the parts shown in the drawings, described in the specifications and pointed out in the appended claims.

Among the objects of the invention are to provide:—

A ticket - dispensing device for the purpose set forth, in which the tickets, drawn from a continuous ticket roll, may be counted off as they are withdrawn from the device, individually or in series, so as to insure accuracy of count in dispensing the tickets; whether they be dispensed individually or in groups.

A ticket-dispensing device in which the ticket strip is reliably locked from further withdrawal as one or more of the tickets are torn from the ticket strip;

A ticket-dispensing device in which the movement to tear a ticket or tickets from the ticket strip serves to automatically lock the ticket strip from further withdrawal;

A ticket-dispensing device provided with a tearing edge that is located on a movable gate which permits the free end of the strip to be readily grasped by the thumb and finger and which constitutes tearing means by which a ticket or tickets are torn from a continuous strip,

And other improvements in ticket dispensing machines as will hereinafter more fully appear.

In the drawings:—

Figure 1 is a perspective view of a roll ticket dispensing machine embodying my invention.

Fig. 2 is a fragmentary section thereof showing the gated dispensing guide and associated mechanism.

Fig. 3 is a similar view showing the fa-

cility with which the finger and thumb may grasp the free end of the ticket strip.

Fig. 4 is a transverse section on the line 4—4 of Fig. 2.

Fig. 5 is a perspective view of the ticket dispensing guide.

As shown in the drawings, 10 designates the base of the device which may be formed of any suitable heavy material to support a ticket roll bracket 11 in which is mounted a reel 12 for supporting a roll 14 of tickets 15. The reel bracket 11 may be otherwise supported from a fixed or stationary support.

16 designates a ticket strip guiding and tearing device, shown herein as located at one end of the base 10. It comprises, as a part thereof, a guide frame 17 (Fig. 5) that consists of a bottom member 18 and upright guide bars or flanges 19. The base 18 is notched at 20 to provide at the sides thereof side arms 21, 21, the ends of which are turned backwardly at 22 to avoid sharp edges at the ends of said side arms.

25 designates a pivoted check plate that is provided between its ends with depending lugs 26, 26 which fit within the side bars or flanges 19 of the guide frame 17, said plate being pivoted to the frame by means of a transverse pivot rod 28. The rear end 29 of the check plate is provided with laterally separated depending lugs 30, 30 which engage in laterally opening notches 31 of the ticket strip. The forward end of the check plate is cut away to provide a notch or opening 32, and at the sides of said notch or opening arms 33, 33 are disposed above the level of the opening 20 in the guide frame 17.

Rising from said arms 33 are posts 35, between the upper ends of which extends a horizontal pivot rod or pin 36. On said rod 36 is hinged a swinging gate 38 that is formed at its lower side to constitute a tearing edge 39, upwardly over which the individual tickets are torn along their transverse scored or parting lines 40. A spring 41, which surrounds the hinge rod 36, normally holds said gate in the oblique position shown in Figs. 1 and 2, while permitting the same to be swung backwardly by the finger, as shown in Fig. 3, when it is desired to grasp the free end of the ticket strip between the thumb and finger to draw the same forwardly. The side arms may be provided at their outer ends with stop shoulders 42 adapted to engage the ends of a

transverse notch 43 in the forward face of the gate to limit the forward movement of the gate.

In the use of the device, after a roll of ticket strip has been placed in the bracket 11, the free end of the strip is trained outwardly through the guide frame 17 between the upright guide bars or flanges 19 and beneath the check plate and the gate 38. When one or more tickets are to be torn from the strip, the gate 38 is pushed rearwardly by the finger when the thumb and finger are in the act of grasping the front edge of the strip, the thumb engaging the lower face of the ticket through the opening 20 and the finger engaging the upper face of the ticket through the opening 32, as indicated by the dotted lines in Fig. 3. Said strip when drawn outwardly is pulled slightly upwardly so as to engage the forward ends of the arms 33. This engagement of the ticket strip with the free ends of the arms 33 has the effect of swinging the forward end of the check plate upwardly about its pivot 28, and thereby swinging the rear end thereof downwardly and pressing the lugs 30 of said plate against the upper face of the ticket strip which is being drawn outwardly thereunder. Therefore as the lugs come opposite the side notches 31 of the ticket strip, they are pressed into said notches and produce a perceptible check in the advance of the strip such as will enable the operator to know when a ticket length has been withdrawn and also to count the individual tickets when a number of them are withdrawn at one time. The distance between the lugs 30 and the tearing edge of the gate 38 is such that when the lugs are engaged with a pair of notches 31 in the rear of the gate, one of the tearing lines 40 of the strip, which lines are disposed opposite to the pairs of notches, is located just beneath the tearing edge of the gate. Therefore by sharply lifting the forward end of the strip upwardly, the ticket or tickets withdrawn may be torn off. Furthermore, by reason of the fact that the sharp lift of the ticket strip against the forward end of the check plate causes the rear lugged end of the plate to be depressed, said lugs engage the pair of subjacent notches so as to hold the ticket strip from being pulled outwardly during the tearing operation. It will thus be seen that the device is positive to count the number of tickets being withdrawn and is also positive to hold the strip in place to tear the tickets at a tearing or parting line. The forward ends of the arms 33 of the check plate are sharpened to constitute the ends of the tearing edge of the device.

While reference has hereinbefore been made to the dispensing of roll tickets and the device is illustrated with special refer-

ence to dispensing this form of ticket, it will be understood that my invention may be embodied in machines or devices for dispensing other forms of individual tablets, checks, labels or the like from a continuous strip. It will be also understood that the invention is capable of assuming other embodiments within the spirit and scope of the claims hereto appended, and the invention is not therefore limited to the particular embodiment herein shown, except as the details thereof are hereinafter made the subject of specific claims and as imposed by the prior art.

I claim as my invention:

1. A device for dispensing tickets from a continuous strip, comprising means to hold a continuous strip; a guide outwardly through which the strip is drawn, a tearing member for the strip and means under the control of a withdrawn portion of the strip embracing a counting projection adapted to engage markings on the strip and operating to serially check the tickets of the strip for the purpose of counting the tickets and to positively lock the strip during the tearing operation.

2. A device for dispensing tickets from a continuous strip marked at intervals with notches to produce ticket sections, comprising a holder for the strip; a guide and tearing device through which the strip is drawn, and means under the control of a withdrawn portion of the ticket strip and co-operating with the notched portions of the strip to successively check or count off ticket sections as the strip is continuously withdrawn, and to positively lock the ticket from further withdrawal during the tearing operation.

3. A device for dispensing tickets from a continuous strip marked at intervals with notches comprising a strip holder from which the strip is withdrawn; a guide for the strip, and a pivoted element provided at one end with a tearing edge to sever individual tickets and at its other end with a strip checking and locking means to engage said notches, said pivoted element being acted upon by continuous withdrawal of the strip to check the tickets withdrawn and to lock the strip from withdrawal when the strip is raised against said edge.

4. A device for dispensing tickets or the like from a continuous strip, comprising a holder for the strip; a guide through which the strip is withdrawn, embracing a pivoted member which carries at its forward end a tearing edge upwardly against which the strip is forced to tear the strip, and counting means at the rear end of said pivoted member, adapted to engage markings in the strip and controlled by the swinging movement of said member to successively engage said markings to check off ticket

- sections as the strip is continuously withdrawn and to positively arrest further withdrawal of the strip when the strip is raised against the tearing edge during the tearing 5 operation.
5. A device for dispensing tickets or the like from a continuous strip of that kind which is notched or perforated to divide the strip into individual tickets, comprising a 10 holder for the strip; a guide through which the strip is withdrawn; a pivoted check plate provided at one end with a projection to engage said perforations, and provided at its other end with a tearing edge.
10. In a device for the purpose set forth, in combination, a guide, a check plate hinged thereto and provided at one end with strip retarding and positive strip locking means and at its other end with a swinging 15 member formed with a tearing edge.
15. A device for dispensing tickets or the like from a continuous strip that is notched or perforated to divide the strip into individual tickets, comprising a holder for the strip; a guide through which the strip is 20 withdrawn; a pivoted check plate provided at one end with a projection to engage said perforations, and a swinging gate carried by the other end of said plate and provided with a tearing edge.
25. A device for dispensing tickets or the like from a continuous strip that is marked at intervals to produce ticket sections, comprising a holder for the strip; a guide comprising a bottom member notched at its 30 front end and provided with upstanding flanges; a check plate pivoted between its ends and provided at its rear end with a retarding projection to engage the markings of the strip, and a gate hinged to the other 35 end of said plate and formed at its lower end to provide a tearing edge.
30. A device for dispensing tickets or the like from a continuous strip that is marked at intervals to produce ticket sections, comprising a holder for the strip; a guide comprising a bottom member notched at its front 40 end and provided with upstanding flanges; a check plate pivoted between its ends and provided at its rear end with a retarding projection to engage the markings of the strip, said plate being notched opposite to the notch of the guide bottom member and provided at the sides of its notch with upstanding arms, and a gate hinged to said 45 arms and provided at its lower end with a tearing edge.
45. In a device for the purpose set forth, in combination, a guide, a check plate hinged thereto and provided at one end with counting means adapted to engage markings on a 50 strip to momentarily retard and to positively lock the strip, and operated by swinging movement of said plate, said plate being provided at its other end with a tearing 55 edge.
5. In a device for the purpose set forth, in combination, a guide comprising a floor which is notched at its forward end and provided with upstanding guide flanges, a check 60 plate over the said floor between said flanges with means to pivot it to the flanges, said check plate being provided at its rear end with strip-retarding means and at its front end with a tearing edge.
10. In a device for the purpose set forth, in combination, a guide comprising a floor which is notched at its forward end and provided with upstanding guide flanges, a check 65 plate over the said floor between said flanges with means to pivot it to the flanges, said check plate being provided at its rear end with strip-retarding means and at its front end with a tearing edge.
15. In a device for the purpose set forth, in combination, a guide comprising a floor which is notched at its forward end and provided with upstanding guide flanges, a check 70 plate over the said floor between said flanges with means to pivot it to the flanges, said check plate being provided at its rear end with strip-retarding means and at its front end with a tearing edge.
20. In a device for the purpose set forth, in combination, a guide comprising a floor which is notched at its forward end and provided with upstanding guide flanges, a check 75 plate over the said floor between said flanges with means to pivot it to the flanges, said check plate being provided at its rear end with strip-retarding means and at its front end with a tearing edge.
25. In a device for the purpose set forth, in combination, a guide comprising a floor which is notched at its forward end and provided with upstanding guide flanges, a check 80 plate over the said floor between said flanges with means to pivot it to the flanges, said check plate being provided at its rear end with strip-retarding means, and notched at its forward end above the notch of the guide floor, and a gate hinged to said notched end 85 of the guides on a pivot above said guides and formed with a tearing edge.
30. A device for dispensing tickets from a continuous strip, comprising means to hold a continuous strip; a guide outwardly 90 through which the strip is drawn, a tearing member for the strip, and means under the control of a withdrawn portion of the strip, embracing a counting projection adapted to engage markings on the strip, and operating 95 to serially check the tickets of the strip for the purpose of counting the tickets and to positively lock the strip during the tearing operation, said tearing means, when in operative position, and counting projection being spaced a distance equal to the length of a ticket.
35. In testimony whereof, I have hereunto set my hand at Chicago, Illinois, this 29th day of June, 1916.

JAMES S. ARCUS.
